PUMPING UNIT FOR RECIPROCATING TYPE PUMP

William H. Hunter, Aurora, Mo., assignor, by mesne assignments, to B. K. Sweeney Manufacturing Company, Inc., Denver, Colo.

Application September 3, 1954, Serial No. 454,078

1 Claim. (Cl. 103—179)

This invention relates to a novel pumping unit for a reciprocating type pump and which is adapted for operation in a pump working barrel.

The present invention constitutes an improvement on my prior U. S. Letters Patents Nos. 2,240,780 and 2,475,705, issued May 6, 1941, and July 12, 1949, respectively, and entitled Flat Groove Valve Body and Packing Means Therefor and Expansible Ring and Groove Therefor, respectively.

More particularly, it is a primary object of the present invention to provide a reciprocating type pumping unit composed of a minimum number of parts and which is so constructed that the parts will be subjected to a minimum amount of wear.

Another object of the invention is to provide a unit capable of being applied to or removed from a working barrel while fully assembled and which is capable of being readily dismantled for replacement of parts, when required.

A further object of the invention is to provide a pumping unit utilizing frictional contact between certain of the parts thereof with one another and with the working barrel to effect a most efficient operation of the pump and by means of which the necessity of providing a pumping unit with expansible type sealing means is obviated.

Various other objects and advantages of the invention will hereinafter become more fully apparent from the following description of the drawings, illustrating a presently preferred embodiment thereof, and wherein:

Figure 1 is a longitudinal sectional view of a portion of the working barrel of a pump showing the pumping unit in side elevation disposed therein;

Figure 2 is an enlarged fragmentary vertical sectional view taken substantially along a plane as indicated by the line 2—2 of Figure 1;

Figure 3 is a similar view taken substantially along a plane as indicated by the line 3—3 of Figure 1;

Figures 4 and 5 are cross sectional views, taken substantially along planes as indicated by the lines 4—4 and 5—5, respectively, of Figure 2;

Figure 6 is a cross sectional view taken substantially along a plane as indicated by the line 6—6 of Figure 3;

Figure 7 is a longitudinal fragmentary sectional view similar to a portion of Figures 2 or 3 and illustrating a different position of parts of the pumping unit from the position of the parts as shown in Figures 2 and 3, and

Figure 8 is a top plan view of the pump plunger shown removed from the remainder of the pumping unit and detached from the sucker rod.

Referring more specifically to the drawings, the pumping unit in its entirety and comprising the invention is designated generally 10 and is illustrated in Figures 1 to 5 in an operative position in a working barrel 11. Said working barrel 11, beneath the pumping unit 10, is provided with a fixed valve seat 12, as best seen in Figure 3, having a cage 13 secured thereon and disposed thereabove for re-

2

stricting movement of a ball valve 14 which normally assumes a closed seated position on the seat 12 by gravity.

The pumping unit 10 includes a plunger, designated generally 15, a substantial part of which is formed by a rod 16 of circular cross section having an externally threaded lower end 17 the maximum diameter of which is no greater than the diameter of the remainder of said rod 16, as seen in Figure 3. The plunger 15 includes a collar 18 formed integral with and disposed around the upper end of the rod 16 and which is of substantially larger diameter than said rod. The plunger 15 also includes an integral portion 19 which extends upwardly from the collar 18 and which is of smaller diameter than said collar. The plunger part 19 is provided with flat surfaces forming wrench lands 20. The upper end of the plunger 15 is formed by a threaded stem 21 which extends upwardly from the upper end of the plunger part 19 and which is of smaller diameter than said part 19. The stem 21 is threaded into a downwardly opening internally threaded socket 22 formed on the lower end of a sucker rod or the like 23 and which extends downwardly into the working barrel 11 for supporting the pumping unit 10 therebeneath and above the cage 13 of the standing valve 12, 14.

25 The pumping unit 10 includes a plurality of corresponding sleeves, each designated generally 24, and each including an elongated sleeve portion 25 having an enlargement at the upper end thereof forming a head 26 which is radially enlarged relatively to the sleeve portion 25. Each sleeve 24 has a bore 27 of uniform diameter from end-to-end thereof extending longitudinally therethrough and accordingly extending through the sleeve portion 25 and the head 26, as seen in Figures 2 and 3. Thus, the head 26 is annular in form and has a flat upper surface 28 which is disposed in a plane at a right angle to the longitudinal axis of the sleeve 24. The head 26 has an annular downwardly and inwardly inclined and beveled underside 29 which combines with the flat top surface 28 to form a relatively narrow annular peripheral surface 30. As seen in Figures 2 to 5, the sleeve portion 25 is provided with a plurality of longitudinally and circumferentially spaced integral outwardly extending projections 31 having convexly rounded outer ends 32 which are disposed concentric to the axis of the sleeve 24. Each sleeve portion 25 is preferably provided with a group of projections 31 adjacent each end thereof, each of which group preferably comprises four projections which are equally spaced circumferentially around the sleeve portion 25.

50 The pumping unit 10 also includes a plurality of valves, each designated generally 33, and each comprising an elongated cylinder the wall which is of substantial thickness, as illustrated in Figures 2 and 3, and which wall has a flat annular lower end 34 which is disposed at a right angle to the axis of the cylindrical valve. The cylinder forming the valve 33 has a downwardly or inwardly inclined or beveled upper end or top surface 35 having a pitch corresponding to the pitch of the undersides 29 of the sleeve heads 26. Said top surface 35 of the cylindrical valve body 33 is provided with integral circumferentially spaced raised portions or projections 36 having top surfaces disposed parallel to the beveled upper end 35 of the valve.

55 The pumping unit 10 additionally includes a collar 37 having a flat top surface 38, corresponding to the top surfaces 28 of the heads, a central bore 39, of the same diameter as the bores 27, and an outer peripheral portion 40 of substantially the same width and diameter as the peripheries 30 of the heads. The collar 37 is also provided with a downwardly and inwardly inclined or beveled annular underside 41 which differs from the beveled undersides 29 of the heads in that the beveled

portion 41 terminates in outwardly spaced relation to the wall of the bore 39 and the collar 37 is provided with a flat bottom surface 42 which is disposed parallel to the top surface 28 and which is relatively narrow radially.

Further, the pumping unit 10 includes a nut 43 having a threaded bore sized to threadedly engage the threaded rod end 17. The nut 43 has a substantially flat upper end 44 disposed at a right angle to the axis of the nut.

To assemble the pump plunger 10, one of the sleeves 24 is slid upwardly on the rod 16 so that the flat top surface 28 thereof will abut against the underside of the collar 18. One of the valve cylinders 33 is then applied upwardly on the rod 16 and is positioned around the sleeve portion 25 of the applied sleeve 24 and with the outer ends 32 of the projections 31 frictionally engaging the bore 45 of said valve cylinder. Said bore 45 and also the outer surface or periphery 46 of each valve 33 are ground and otherwise finished so that the periphery 46 will be of a uniform diameter for an exact working fit in the pump barrel 11. Likewise, the outer ends 32 of the projections are ground and otherwise finished to have an exact working fit in the ground bore 45 of the valve cylinder 33. It will also be apparent that the valve cylinder 33 may be applied to the sleeve 24 and the two parts as thus assembled then positioned on the plunger rod 16. The other set of sleeves 24 and valve cylinders 33 are thereafter applied, in either of the aforementioned manners, beneath the uppermost sleeve and valve cylinder. The collar 37 is then applied to the plunger rod 16 beneath the lowermost sleeve and cylinder, as seen in Figure 3, after which the nut 43 is applied to the lower threaded rod end 17 and tightened so that its flat upper surface 44 will abut against the flat bottom surface 42 of the collar 37. The nut 43 is tightened sufficiently so that the top surface 38 of the collar 37 will abut against the flat lower end of the lowermost sleeve portion 25 and so that the head of said sleeve and the sleeve disposed thereabove will each have its flat top surface 28 abutting against the flat lower end of the sleeve portion 25 disposed immediately thereabove. The upper surface 28 of the uppermost sleeve head 26 will abut against the underside of the plunger collar 18.

The valve cylinders 33 are of a length, including their projections 36, less than the spacing between the surfaces 28 and 38 and the undersides 29 disposed thereabove. As seen in Figures 1, 2 and 3, the diameters of the heads 26 and collar 37 are less than the diameter of the bore of the working barrel 11 to provide an annular passage between the wall of the working barrel 11 and the peripheries 30 of the heads 26 and the periphery 40 of the collar 37. The wall of each valve cylinder 33 is of a thickness substantially greater than the spacing between the wall of the working barrel 11 and said peripheries 30 and 40, so that when the plunger 15 and sleeves 24 are raised relatively to the valve cylinders 33, approximately the inner half of said cylinder bottom surfaces 34 will abut flush against the outer portions of the top surfaces 28 and 38.

Assuming that the pumping unit 10 is in a lowermost position, as illustrated in Figures 1 to 3, as the plunger 15 is pulled upwardly by the sucker rod 23 the valves 33 will be caused to move upwardly with the plunger by the engagement of their bottom surfaces 34 on the surfaces 28 and 38. The contact of the surfaces 34 with the surfaces 28 and 38 will seal off the part of the working barrel 11 disposed above the pumping unit 10 and the part thereof disposed therebeneath. Thus, as the unit 10 moves upwardly a suction will be created therebeneath for unseating the valve 14 to cause the liquid being pumped to be drawn into the working barrel through the valve seat 12 for partially filling the expanding chamber below the unit 10. As the plunger 15 commences its downstroke with the sucker rod 23 said plunger and the sleeves 24 will initially move downwardly relative to the valves 33 due to the greater area of frictional contact had by the valves 33 with the working barrel

11 than the frictional contact of the projection ends 32 with the valve bores 45, so that during the downstroke of the plunger 15 the valves 33 will have the upper surfaces of their projections 36 in contact with the undersides 29 of the heads 26, causing the valves 33 to move with the plunger and sleeves when this contact is established. During the downstroke of the pumping unit 10, the liquid or other medium being pumped located in the chamber of the working barrel between the pumping unit 10 and the valve seat 12 will be forced upwardly through the pumping unit, due to the fact that the valve 14 will resume a closed position as soon as upward movement of the pumping unit ceases. Consequently, the pumped medium, during the downstroke of the unit 10, will pass upwardly between the working barrel and collar periphery 40, inwardly between the bottom surface 34 of the lowermost valve 33 and the top collar surface 38 and thence upwardly between the lowermost sleeve portion 25 and the bore 45 of the lowermost valve. The pumped medium will then pass upwardly and outwardly between the projections 36 and between the spaced surfaces 35 and 29 of the adjacent sleeves 24 and valves 33, between the peripheries 30 and the bore wall of the working barrel 11 and similarly between the top surfaces 28 and bottom surfaces 34 which are disposed thereabove and upwardly between the other valve bores 26 and sleeve portions 25.

Thereafter, on the next upstroke of the sucker rod 23 and plunger 15, said plunger and the sleeves 24 will initially move upwardly relative to the valves 33 which, in the same manner as previously described, will be retained by frictional engagement with the working barrel 11 against upward displacement until their bottom surfaces 34 contact the top surfaces 28 and 38 to form seals for trapping the pumped medium disposed above the collar surface 28 so that said pumped medium is lifted by the pumping unit during the upstroke thereof and, at the same time, the expanding chamber immediately beneath the pumping unit 10 is refilled as previously described. Additionally, the fluid impinging upon the inclined top surfaces 35 of the valves additionally assists to hold the bottom valve surfaces 34 properly seated on the top surfaces 28 and 38 for sealing the pumping unit against downward escape of the pumped medium during its upstroke. It will be obvious that the greatest pressure will exist within the upper valve 33 and any of the pumped medium which may escape past the bottom surface 34 thereof and the surface 28 on which it rests, will be trapped by the valves 33 disposed therebeneath. It will also be apparent that the pumping unit will be self-cleaning in that the pumped medium flowing upwardly therethrough will flush out any dirt or sediment which might otherwise collect therein to insure a proper seating engagement between the parts.

From the foregoing it will be apparent that a valve unit of extremely simple construction has been provided utilizing the valves 33 the walls of which are solid and uninterrupted. It will also be apparent that all parts of the pumping unit may be formed of metal for reducing wear and minimizing the need for replacement of parts. It will also be understood that the pumping unit may include any desired number of sleeves 24 and valves 33.

Various other modifications and changes are contemplated and may obviously be resorted to, without departing from the spirit or scope of the invention as herein-after defined by the appended claim.

I claim as my invention:

In combination with a working barrel and a plunger reciprocably disposed therein; a pumping unit comprising an elongated sleeve mounted on the plunger and having an enlargement at an upper end thereof forming a head, means securing the sleeve immovably to the plunger including a collar fixed to the plunger and having a flat upper surface abutting against a lower end of the

sleeve, an elongated cylinder of rigid unbroken construction loosely disposed around the sleeve between the collar and head and of a length less than the spacing between the head and collar, said cylinder constituting a valve and having an outer diameter greater than the outer diameters of the head and collar and such as to provide a close fitting sliding engagement of the cylinder in the working barrel, said cylinder having an inner diameter less than the outer diameters of the head and collar for confining the cylinder therebetween, a lower end of the cylinder seating against the outer part of the upper surface of the collar during upward travel of the cylinder with the collar and sleeve for sealing off the working barrel above and beneath the collar, and said sleeve, beneath the head, having outwardly extending projections, said projections having outer ends frictionally engaging against the wall of the cylinder for

supporting the cylinder on the sleeve and for maintaining the sleeve and collar centered relative to the cylinder and working barrel, the frictional engagement of the projections with the cylinder being less than the frictional engagement of the cylinder with the working barrel to cause the cylinder to move with the sleeve only when engaged by either the head or collar, and means forming passages between the head and cylinder when the cylinder is engaged by the head.
